No. 887,412.

PATENTED MAY 12, 1908.

G. MITTINGER, JR.

WASHBOARD.

APPLICATION FILED SEPT. 26, 1907.

UNITED STATES PATENT OFFICE.

GEORGE MITTINGER, JR., OF LAKWOOD, OHIO.

WASHBOARD.

No. 887,412.

Specification of Letters Patent.

Patented May 12, 1908.

Application filed September 25, 1907. Serial No. 394,510.

To all whom it may concern:

Be it known that I, GEORGE MITTINGER, Jr., a citizen of the United States, residing at Lakewood, in the county of Cuyahoga and 5 State of Ohio, have invented certain new and useful Improvements in Washboards, of which the following is a specification, reference being had therein to the accompanying drawing.

10 My invention relates to improvements in wash boards, and pertains more particularly to a board composed wholly of metal.

The object of my invention is to provide a wash board composed of metal, and in which 15 the several parts are so assembled and connected as to form a more simple, cheap and effective wash board, and also providing a non-rusting board.

In the accompanying drawing, Figure 1, is 20 a side elevation of my improved wash board. Fig. 2, is a vertical sectional view taken on the line 2—2 of Fig. 1. Fig. 3, is a top plan view of Fig. 1. Fig. 4, is an enlarged perspective view taken on the line 4—4 of Fig. 25 1. Fig. 5, is an enlarged perspective sectional view taken on the line 5—5 of Fig. 1.

My invention consists in constructing a wash board wholly of sheet metal, and securing it together by solder, and crimping 30 the several parts together, thus making a more simple, cheap and effective wash board.

My invention further consists in coating the entire board with a non-rusting material and thus forming a non-rusting wash board.

35 Referring now to the drawings, 1 and 2 represent the legs or side bars of my improved board, which, as hereinafter more fully described, are formed of sheet metal rolled or bent into approximately cylindrical members. Between the legs or side bars is the scrubbing board or surface 3 which is made of corrugated sheet metal having its ends entering the legs or side beams. The 40 said scrubbing board does not extend to the ends of the legs forming the two feet portions 4 and 5 below the board. The said scrubbing board ends a considerable distance below the upper end of the legs or side beams to leave space for the soap receptacle, as in 45 50 the usual wash-board.

The soap receptacle is formed of a sheet of corrugated metal 6, although plain metal could be used, the corrugated metal adding strength. The corrugations of the metal 5 forming the soap receptacle are vertical, thus

allowing the water to drain downward out of the receptacle. This metal sheet is obliquely arranged, and has its upper end extending horizontally forward over the upper ends of the legs 1 and 2, as indicated at 7, and soldered thereto. The extreme forward edge of 60 said horizontal portion is rolled at 8 to form a good finish and to prevent any of the rough edges of the metal being exposed. The lower end of the receptacle plate 6 is bent outwardly at 9, and soldered to the upper end 65 of the wash-board as indicated at 10. The sides 11 of the receptacle plate are bent forward and outwardly, as indicated at 12, into the legs or beams as shown in Fig. 5, thus 70 securing the plate within the legs, all of which will be later described.

Extending transversely across the lower end of the receptacle plate is a horizontal plate 13, which has its ends turned downwardly at 14 and upwardly at 14' around the plate 15, which is crimped in the legs, as 75 shown in dotted lines, Fig. 5.

The legs or side bars of my improved board are composed of a sheet of metal doubled at approximately the center, and having formed therein a hollow rib 16, the ends 80 extending therefrom and curved to form the semi-circular portion 17 and 18. The ends of the plate are then extended inwardly, as indicated at 19, and 20, and between which the sides of the scrubbing board extend, and also 85 between which extends the outwardly-turned portion 12 of the receptacle plate. The end 19 of the plate forming the leg terminates 90 at 21 within the hollow beading, while the portion 12 of the receptacle plate and the outer end of the scrubbing plate extends around the end 19 and terminates at 22 and 23. The other end 20 of the plate forming the leg extends 95 around the ends of the scrubbing plate and the receptacle plate and ends at 24, and when in this position the hollow beading is firmly crimped together, forming a solid beading and firmly and securely locking the 100 several parts together against any movement whatever, and at the same time obviating the necessity of rivets or other fastening means for securing the several parts together, and also making a smooth finish to 105 the article, and doing away with rough corners and other objectionable features.

The slot in the legs or side bars of the board below the coiled portion 25 of the scrubbing board 6 is filled in any desired 110

2
manner, making a finished appearance, as well as preventing the collecting of dirt etc. therein.

Having thus described my invention, what I claim and desire to secure by Letters Patent, is:—

1. A metallic wash board, comprising side beams formed of sheet metal bent into the form of a tube, and having a hollow rib formed in one side and a scrubbing plate having its ends passing through the tube and into the rib and crimped therein.

2. A metallic wash board, comprising a side beam formed of sheet metal bent into the form of a tube and having a hollow rib formed in one side, and a scrubbing plate and a soap receptacle having their ends passing through the tube and into the rib and crimped therein.

3. A metallic wash board comprising side beams formed of sheet metal bent into the form of a tube and having a hollow rib formed in one side, and a scrubbing plate and a soap receptacle having ends passing through the tube and into the rib and interlocking with the ends of the sheet of metal forming the side beams.

4. A metallic wash board comprising side beams formed of sheet metal bent into the form of a tube, having a hollow rib formed in one side, and a scrubbing plate having its ends passing through the tube and into the rib and interlocking with the ends of the sheet of metal forming the side beams.

5. A metallic wash board comprising legs each formed of a metal sheet bent into the

form of a tube having a hollow rib in one side, the ends of said sheet being bent inwardly from the side opposite the rib and extending within the rib, and a scrubbing plate having its ends entering the tubes between the inwardly-turned ends of the sheets forming the same and each of its extreme ends lying within the hollow rib and turned inwardly and hooked around one end of the sheet forming the tube while the other end of said sheet is bent around upon the said turned end of the scrubbing plate and within the rib.

6. A metallic wash board comprising legs formed of a metal sheet bent into the form of a tube having a hollow rib in one side, the ends of said sheet being bent inwardly from the side opposite the rib and extending within the rib, a scrubbing plate and a soap receptacle having their ends entering the tubes between the inwardly-turned ends of the sheet forming the legs, and their ends lying within the hollow rib and turned inwardly and hooked around one end of the sheet forming the tube, while the other end of said sheet is bent around upon the said turned end of the scrubbing plate, and the soap receptacle and brackets secured within the tube and extending inwardly, and a transverse plate supported by said brackets.

In testimony whereof I affix my signature in presence of two witnesses.

GEORGE MITTINGER, JR.
